Fig. 1

Fig. 2

Fig. 3

FIG. 1 is a perspective view of a tire embodying our new design, it being understood that the full line portion is repeated throughout the circumference of the tire, shown by means of broken lines;

FIG. 2 is an enlarged fragmentary plan view of the full line portion shown in FIG. 1, and

FIG. 3 is a fragmentary sectional view taken substantially on the plane indicated by line III-III of FIG. 2, but also on the same scale as FIG. 2.

The dominant features of our design reside in those portions shown in full lines in the drawings.

We claim:

The ornamental design for a tire, substantially as shown and described.
